UNITED STATES PATENT OFFICE

1,966,595

DISPENSING DEVICE

Philip D. Parsons, Swarthmore, Pa., assignor to
Scott Paper Company, a corporation of Pennsylvania

Application October 21, 1932, Serial No. 638,887

5 Claims. (Cl. 242—55.2)

My invention relates to a dispensing fixture for paper toweling in roll form; and my object is to so construct the operating members of the fixture that they and the fixture as a whole may be fabricated from stamped sheet metal providing an efficient and inexpensive device for dispensing roll paper, and more particularly towels made therefrom.

My object is furthermore to so shape the parts 10 that a compact collapsible structure may be provided capable of being adjusted for transportation, with provision of minimum space requirements and low cost.

The dispensing fixture forming the subject 15 matter of the present application, while an improvement upon the fixtures described in Letters Patent No. 1,815,068, dated July 21, 1931, and also in my pending application Serial No. 577,748, filed November 28, 1931, is of a simpler and less 20 expensive construction than the fixtures therein set out while, at the same time, being more efficient in use.

My invention also has for an object the provision 25 of a roll dispensing fixture which shall be operable for supporting a roll of paper toweling in such manner as to be held against freely unwinding and yet readily unwind by a pull upon the paper web sufficient to overcome the normal friction applied to the paper roll in use.

In the present fixture, as in the aforesaid Letters Patent and application, I employ a base 30 adapted to be fastened to the wall and provided with two hinged arms jointed to the base and having their free ends so constructed as to receive and support the paper roll in a journaled manner, whereby it may be rotated by mere pulling upon the paper web and, at the same time, overcome a frictional drag upon the paper roll during the dispensing act. The improvements of 35 the present fixture, however, are directed to the simplification of the operative parts, more particularly in the manner of hinging the arms, applying spring pressure upon the paper roll to prevent spinning or too free unwinding, and in so 40 constructing the essential parts that the dispensing fixture as a whole may be collapsed and packed for transportation in a very materially reduced space.

My object in the present construction is also 45 to materially cheapen the cost of manufacture of the improved paper roll dispensing fixture, including the making of the several parts thereof, while retaining the high standard of efficiency.

With these and other objects in view, my invention consists in the features of construction

hereinafter described in the specification and pointed out in the claims.

Referring to the drawing: Fig. 1 is a side view of a dispensing fixture embodying my invention; Fig. 2 is a plan view of the same, with a portion in section; Fig. 3 is a plan view of the fixture with the paper roll removed and the supporting arms collapsed or folded for convenience in transportation; Fig. 4 is an end view of my improved fixture; and Fig. 5 is an enlarged view of a portion of the base and one of the arms adjusted in position for sustaining the paper roll.

2 is a stamped sheet metal bracket or base reinforced with ribbed portions 3, said base also having slotted depressions 4 through which fastening screws may extend. As is shown in the several figures, the base near each end is provided with flanged portions in pairs stamped or bent outwardly from the body, as indicated at 5, and to each pair of flanged portions are hinged 65 the respective hinged arms 6 and 7. The arms are each provided with flanged hinged portions 13 arranged at a distance apart so as to fit snugly to the pairs of flanges 5, before referred to. These flanges 5 and 13 are hinged together by 70 rivets 9, and the parts are so shaped that the arms 6 and 7 may be moved downward toward the base 2 to assume the positions indicated in Fig. 3. Furthermore, these hinged arms have their flanges 75 13 so shaped that when the arms are adjusted to stand outwardly from the base 2, as indicated in Figs. 2 and 5, said arms positively contact with the base after they assume the outward position, and thereafter the said arms 6 and 7 are prevented from any further outward movement preliminary to receiving the paper roll.

The outer ends of the arms 6 and 7 are provided with buttons 11 riveted to the arms at 11a; and the arms have their ends surrounding the button made flat as indicated at 10. Instead of 95 employing a rivet 11a for attaching the button, the union may be by the well known spot-welding method, if so desired. The annular space upon said ends 10 beyond the perimeter of the buttons 11 is of sufficient area to press against the core R and paper webbing of the roll P adjacent thereto, so as to make a frictional contact between said annular surface 10 of the arms and the ends of the paper rolls, as shown in Fig. 2, for putting a 100 drag upon the paper and prevent spinning. The button portions 11 are disks with rounded perimeters and of a diameter that will allow them to easily enter the open end of the tubular core R of the paper roll, as shown in Fig. 2. The an- 105

nular flat portion 10 at the upper ends of the arms is assured by the stamped portions 7a which are arranged between said annular portion 10 and the main body of the arms 6 and 7, and it is 5 desirable that this annular portion should be so shaped relatively to the arms that it will press upon the end of the core and paper roll entirely about the axis thereof, as clearly shown in Fig. 2. Rigidity is given to this annular friction crea- 10 ting flat portion by the presence of the button 11 which is riveted or spot-welded centrally of said annular flat portion. Between the said flat portion and the hinge 9, the arms 6 and 7 are provided with considerable elasticity and said 15 elasticity is designed to cause the button ends of the arms 6 and 7 to yieldingly press toward each other.

The spring action of the arms 6 and 7 is illus- 20 trated in Fig. 5, wherein the solid lines repre- sent the position of the arm when turned out- 25 wardly from the base 2 and before the roll of paper is put into place, as in Fig. 2. In Fig. 5, there is no lateral pressure put upon the arm 7 by the paper roll, yet at this time the heel 13a of the flange portions 13 is in contact with the base plate 2. When the paper roll is inserted between the two arms 6 and 7, the button por- 30 tions 11 are inserted in the hollow core ends and the annular plate portions 10 are permitted to press upon the ends of the roll and core to put friction thereon, as before stated. When the paper roll is to be introduced, the spring arms 6 and 7 are forced apart and the paper roll is re- 35 ceived between the button bearings 11, 11. When this is being done, the spring arms are moved from the solid line position to the dotted line position in Fig. 5. Upon introducing the paper roll between the button ends of the arms 6 and 7, they are released and under their spring pres- 40 sure they are moved toward each other and hence move from the dotted line position to the solid line position in Figs. 2 and 5. With this ad- 45 justment of the arms upon the base, both the arms 6 and 7 assume definite pressure positions, as at this time the heels of the flanges 13 are pressing upon the base 2 and the spring action of the two arms will be jointly in operation to maintain the relation of the parts as shown in Fig. 2. The friction between the arms and roll 50 ends will continue to be substantially the same.

By making the arms 6 and 7 of spring steel, active spring pressure may be assured to the paper roll ends, with a relatively great saving of space as compared with the character of hinged arms 55 and separate springs shown in my application Serial No. 577,748, aforesaid, all of which enables the over-all length of the dispenser to be con- siderably shortened, thereby reducing the space, weight, and cost.

60 The simplicity in construction of the parts and in the assembling requirements thereof is greatly improved as will be seen from the fact that the two arms are identical and are hingedly attached to the base by four small rivets only; and fur- 65 ther, in that no separate springs are required, since the spring action of the sheet steel arms themselves suffice wholly in this regard.

When it is desired to transport the dispensing 70 fixture, the arms 6 and 7 are turned down about their hinge parts 5, 9, 13, and so as to rest upon the base plate as shown in Fig. 3. It is then packed in this condition and requires much less space than is required for packing the fixture 75 of my application aforesaid. This economy in

space required for shipment, equally applies to the commercial requirements for manufacturing storage.

While it is my object to employ the fixture herein described for use in connection with rolls of paper of the character employed as toweling, I do not restrict myself thereto, as the fixture may be employed for dispensing paper in roll form whether for toilet or commercial uses.

80 It will now be apparent that I have devised a novel and useful construction which embodies the features of advantage enumerated as desirable, and while I have in the present instance shown and described the preferred embodiment thereof which has been found in practice to give satisfactory and reliable results, it is to be understood that I do not restrict myself to the details stated as they are susceptible of modification in various particulars without departing from the 85 spirit or scope of the invention.

90 I claim:

1. In a dispensing fixture for paper in roll form, the combination of a base or bracket for attachment to a wall or other place with two arms respectively hinged to the opposite ends of 100 the base or bracket, whereby said arms may be turned down upon the base or bracket for trans- portation or extended outwardly from said base or bracket when supporting a roll of paper, said arms being formed of spring sheet metal and 105 having means at their free ends for respectively receiving and supporting the opposite ends of the paper roll, and means acting as limit stops for retaining the two arms in substantial parallel 110 relation and causing spring pressure of the free ends of said arms upon the ends of the paper roll.

2. The invention according to claim 1, wherein further, the arms are stamped from sheet steel and each provided with flat button-like means 115 upon which the paper roll is journaled and also having an annular flat portion for securing frictional contact with the ends of the paper roll.

3. The invention according to claim 1, wherein further, the base or bracket is provided with out- 120 wardly arranged flange portions in spaced relation near each of its ends and the hinged ends of the arms are each provided with flange por- tions forming a hinge with the flange portions extending outwardly from the base, and in which 125 the hinge axes are arranged to one side of the spring arms to provide heels which press upon the said base and form limit stops when the spring arms are extended outwardly from said base.

4. A dispensing fixture for paper in roll form, 130 which consists of a base or bracket adapted for attachment to a wall or other place, two arms respectively hinged near the opposite ends of the base or bracket so as to swing inward toward each other into a collapsed relation with respect 135 to the base or bracket and also to swing outward away from each other at substantially right angles to the said base or bracket to receive and support a paper roll, said arms being formed of flat sheet spring metal and having great elas- 140 ticity so as to apply spring pressure upon the ends of the paper roll, and means acting as limit stops between the hinged ends of the arms and the base or bracket to limit the spreading of the arms apart and for normally holding said spring 145 arms in contact with the paper roll.

5. In a dispensing fixture for paper in roll form, the combination of a base and a pair of spring arms yieldingly movable toward and from each other, one at least of said spring arms 150

hinged to the base and formed of flat sheet spring metal having at its free end a journal support for the paper roll and at its hinged end a limit stop to limit the movement of the inner end of the said spring arm away from the paper roll whereby the spring action of the arm itself

provides a pressure upon the paper roll, the spring arms being so formed that when released they automatically close toward each other sufficiently to provide frictional contact on the ends of the paper roll.
